CONTAINER CLOSURE MEANS

Benjamin F. Conner, West Hartford, and William F. Schmalz, Rockville, Conn., assignors to Colt's Patent Fire Arms Manufacturing Co., Hartford, Conn., a corporation of Connecticut

Original application May 4, 1934, Serial No. 723,865. Divided and this application July 30, 1934, Serial No. 737,528. Renewed January 27, 1936

17 Claims. (Cl. 215—7)

This invention relates to container closure means of the type having a readily breakable portion which is necessarily broken when the closure means or one member thereof is removed 5 to permit access to or discharge of the container contents. A closure means of this character when properly put in place on a container serves, so long as it remains unbroken, as a definite indication to the ultimate consumer and to each 10 intermediate distributor or dealer who handles the package that the original contents are intact and that there has been no substitution or adulteration. More particularly the present invention relates to container closure means such as 15 disclosed in our copending application, Serial No. 723,865, of which this present application is a division.

In a container closure means of this type there 20 is a readily breakable indicator member which may be formed to also constitute a closure for the container. Associated with the readily breakable indicator member is a concealed device which permits free movement of the indicator in the closing direction into its normal position but 25 which automatically serves to break a portion of the indicator member upon movement thereof in the opening or unsealing direction. The indicator member serves as a seal or lock for the closure, and when broken it provides a definite 30 warning to anyone handling the package that the container may have been opened and the contents tampered with. The ultimate consumer or any distributor or dealer, by accepting only a package having the seal or indicator 35 thereof intact, can thereby be certain that he is obtaining the original contents of the package as shown by the trade mark or label or other marking thereon.

The object of the present invention is to provide 40 a container closure means wherein the indicator member or outer closure, instead of being directly connected with the container, is held in place therein indirectly by means of the primary or inner closure. The container may be 45 utilized to prevent simultaneous rotation of the primary and outer closures, but even this is not essential.

Other objects of the invention will be apparent 50 from the following specification and claims.

In the accompanying drawing there is shown 55 several different embodiments of the invention, but it will be understood that the drawing is intended for illustrative purposes only and is not to be construed as defining or limiting the scope of the invention, the claims forming a part of

this specification being relied upon for that purpose.

Of the drawing:

Fig. 1 is a vertical sectional view of a container closure means embodying the invention, the closure means being in place on a bottle which is shown in elevation.

Fig. 2 is a fragmentary plan view of the threaded metallic ring shown in Fig. 1.

Fig. 3 is a view similar to Fig. 1, but showing 10 the indicator member or outer closure turned slightly in the unscrewing direction so as to break the upper portion thereof.

Fig. 4 is a vertical sectional view similar to Fig. 1, but showing an alternative embodiment 15 of the invention.

Fig. 5 is a plan view of the primary closure shown in Fig. 4, this view also showing the metal device interposed between the primary closure and the indicator or outer closure.

Fig. 6 is a detail perspective view of the interposed metal device shown in Figs. 4 and 5.

Fig. 7 is a vertical sectional view of another alternative container closure means embodying 25 the invention.

Fig. 8 is a plan view of the primary closure shown in Fig. 7.

Fig. 9 is a vertical sectional view similar to Fig. 7, but showing another embodiment of the invention.

Referring to the drawing, particularly Figs. 1 to 3, 1 represents a container with which the container closure means embodying the invention may be used, the said container having a mouth or opening 2. The container is shown 35 as being a glass bottle, but it will be understood that the invention may be used with a wide variety of containers.

The indicator element or member is represented at 3, and it is shown as being a complete closure of the cap type entirely covering the opening 2 in the container, but the indicator member is not necessarily a complete closure. Preferably and as shown, the indicator member 3 is provided with an internal thread 4 for normally preventing movement of the said member 3 upward or outward away from the container, the said thread nevertheless permitting relative rotative movement. The indicator member 3 has an externally visible element or portion which is adapted to be 40 readily broken or separated from the remainder of the member. As shown this readily breakable or separable element or portion is at the top, as indicated at 5, being surrounded by an annular zone of weakness shown at 6.

The indicator member 3 may be formed of any one of a variety of materials, but it is preferred to mold the said member from a material of the synthetic resin class. Such a material is somewhat brittle and is readily breakable when provided with a sufficiently thin zone of weakness such as that at 6, and it has the further advantages that it is available in a variety of colors and can be readily molded to provide any desired external trade mark or ornamental design. Synthetic resin material has the further advantage that upon breaking it does not form sharp fragments or splinters dangerous to the person opening the container. Container closures for the same general purpose as the present closure have commonly been made of glass or metal, and have been seriously objectionable because of the likelihood of injury to the hands of the user.

In addition to the indicator member or outer closure 3 there is a separate primary closure 7 which directly engages the container 1 to close the mouth 2 thereof. The closure 7 is covered or at least partly covered by the indicator member or outer closure 3, the relationship being such that the primary closure 7 cannot be removed while the indicator member or outer closure remains in place and unbroken. The closure 7 may be of any one of a variety of types, but it is shown as being of the cap type and as having an internal thread 8 engaging an external thread 9 on the container adjacent the opening 2. The closure 7 may also be molded from a material of the synthetic resin class, and it is provided with a gasket or liner 10 which engages the top of the container 35 or bottle to seal it in the usual manner.

As already stated, the indicator member or outer closure 3, instead of being held in place by reason of direct engagement with the container, is held against removal solely by the primary closure. To this end there is provided a means separate from the container and held by the primary closure, this means being adapted to be engaged by the aforesaid internal thread on the indicator member. The means for engaging the said thread and for thus holding the indicator member may vary in form and it may be a thread formed integrally with the primary closure, but in Figs. 1 to 3, we have shown a threaded metallic ring 11 structurally separate from the primary closure but held in place thereby. As shown the ring 11 is provided with a peripheral rolled thread 12 surrounding the lower part of the primary closure 7 and is provided with an inward projecting flange 13 which engages the bottom of the closure 7 to prevent upward removal. Downward movement of the ring 11 is prevented by the usual bead 14 on the bottle. The ring 11 engages with the container or bottle in such a way as to prevent relative rotation. As shown the bottle is provided above the bead 14 with two opposite lugs 15, 15 which enter notches 16 formed in the flange 13 of the ring.

Associated with the readily breakable portion 5 of the indicator member 3 is a device structurally separate from the indicator member and adapted to permit the said member to be screwed into its normal position, but causing breaking of the portion 5 thereof when the member is turned in the opposite unscrewing direction. Preferably to facilitate the action of the breaking device, the readily breakable portion 5 is provided with internal teeth as indicated at 17. The teeth 17 are preferably very shallow in order to permit removal from the mold, such removal being possible by reason of the resilience of the molded

material while still hot. The teeth as shown in the drawing is somewhat exaggerated in size.

While the invention is not so limited the breaking device may conveniently be a metallic element such as 18 having resilient pawls 19, 19. When the indicator member is being moved or screwed into its normal position, the said pawls 19, 19 freely snap over the teeth 17 of the breakable portion 5; but upon movement of the indicator member in the opposite or unscrewing direction, the pawls 19, 19 automatically engage and hold the said teeth 17 and thereby break the said portion 5. The primary closure 7 serves as the means for supporting the breaking device 18. As shown the closure 7 is provided with a square or otherwise non-circular recess 20 which is of suitable size to receive the device 18 and prevent relative rotation thereof.

In using the closure means shown in Figs. 1 to 3 the ring 11 is first put in place and the primary closure 7 is screwed into position in accordance with usual practice. Then the breaking device 18 is dropped into place in the recess in the closure 7 and the indicator member 3 is screwed into engagement with the thread 12 on the ring 11. It will be observed that as the indicator member is turned the ring 11 is held against rotation by means of the lugs 15, 15 on the bottle, and that the said ring is drawn upward until further upward movement is limited by the engagement of the horizontal flange thereof with the bottom of the primary closure 7.

With the parts thus assembled access to the contents of the container can only be obtained by first forcibly unscrewing the indicator member 3. The pawls 19, 19 being in engagement with the teeth 17, resist the turning movement, and the said pawls are bent upward, thus exerting an upward force on the portion 5 which breaks it in the upward direction as shown in Fig. 3. When the portion 5 has been broken out the remainder of the indicator member 3 can be removed and then the primary closure member 7 can be removed in the usual manner. Inasmuch as the ring 11 is held against rotation on the bottle there can be no tendency for the indicator member 3 to turn the primary closure 7.

From the foregoing description it will be apparent that it is entirely impossible to obtain access to the contents of the container without first breaking out a portion of the indicator member 3. With the indicator member broken at the top, the consumer or in fact any one else handling the package, will know or at least have reason to suspect, that the contents of the container have been tampered with and he should refuse to accept the package. Thus by refusing to accept any package on which the indicator member is not intact, the consumer can positively protect himself against adulteration or substitution of the container contents. It will of course be understood that the indicator member will ordinarily carry a suitable trade-mark to provide additional protection to the consumer.

The construction shown in Figs. 4 to 6 is similar in principle to that shown in Figs. 1 to 3, but it differs in that there is only one auxiliary metallic element, this one element having the functions of the two elements 11 and 18 shown in Figs. 1 to 3. The container or bottle 1 is or may be exactly the same as that shown in Figs. 1 and 3. A primary closure 7^a is provided which may be the same or substantially the same as the closure 7.

A metallic bridge device or yoke 21 is provided

which is shaped to conform to the cross sectional outline of the primary closure 7^a. The said device has a top portion 22 which engages the top portion of the closure 7^a; it has two vertical side portions 23, 23 which engage the sides of the closure 7^a and it has two inward extending horizontal flanges 24, 24 which engage the bottom of the closure 7^a. These horizontal flange portions 24, 24 are notched at 25, 25 to receive the lugs 15, 15 on the bottle. It will be understood that the yoke 21 is sufficiently resilient to enable it to be easily snapped into position after the closure 7^a has been put in place on the bottle. The yoke 21 instead of being provided with definitely formed screw threads as is the ring 11 shown in Figs. 1 to 3, is provided with resilient teeth or pawls 26, 26 which are adapted to engage with a thread on the indicator member. The yoke 21 is also provided at the top with resilient pawls 27, 27 which correspond in function with the resilient pawls 19, 19 on the breaking device 18.

The indicator member or outer closure 3^a is similar to the member 3 shown in Figs. 1 and 3, being provided with an internal thread 4^a and with a readily breakable top portion 5^a. The thread 4^a is preferably of the buttress type so as to be more readily engaged by the resilient pawls 26, 26.

30 In using the closure means shown in Figs. 4 to 6 the primary closure 7^a is first screwed into position in accordance with usual practice. Then the yoke 21 is snapped into place, the notches 25, 25 thereof fitting the lugs 15, 15 on the bottle. 35 With the yoke in place, the indicator member or outer closure 3^a can be put in place, and on account of the resiliency of the pawls 26, 26 this member may be pushed vertically downward without rotation. A slight final rotative movement may be desirable in order to avoid any possible looseness. It will be observed that with the indicator member 3^a in place the pawls 27, 27 cooperate with the teeth on the breakable portion 5^a in the manner that has already been 40 described. With the parts thus assembled access to the contents of the container can only be obtained by first forcibly unscrewing the indicator member 3^a and thus causing the breaking of the portion 5^a thereof. Inasmuch as the yoke is held 45 against rotation on the bottle there can be no tendency for the indicator member 3^a to turn the primary closure 7^a.

In order to avoid any possible accidental unscrewing of the primary closure 7^a by vibration or otherwise, it may be desirable to provide an annular series of ratchet teeth 28 on the closure 7^a and to provide auxiliary resilient pawls 29, 29 on the yoke 21. When such ratchet teeth and auxiliary pawls are provided it will be evident that 50 accidental unscrewing movement of the primary closure is positively prevented.

In Figs. 7 and 8 there is shown a construction which differs from those shown in Figs. 1 to 6 in that the indicator member or outer closure 55 is threaded directly with the primary closure without the use of an auxiliary metallic device such as the ring 11 or the yoke 21. With this construction the bottle 30 may be of entirely standard construction.

70 The primary closure 31 is provided not only with an internal thread to engage the external thread on the bottle 30, but it is also provided with an external thread adapted to be engaged by an internal thread on the indicator member 75 or outer closure. The primary closure 31 may be

of molded material, as shown in Figs. 1 and 4, but there are practical difficulties in the way of economically molding such a closure with both internal and external threads. The closure 31 is preferably therefore formed of metal having 5 a thread 32 rolled therein, there thus being readily provided both an internal thread and an external thread. With the closure 31 formed of metal the necessary resilient pawls 33, 33 can be formed integrally with the top wall of the closure, 10 thus avoiding the necessity for a separate breaking device such as the device 18 shown in Figs. 1 and 3.

The indicator member or outer closure 3^b is formed with an internal thread 4^b adapted to engage the thread on the exterior of the closure 31. It is also provided with a readily breakable top portion 5^b similar to the readily breakable top portion 5 shown in Figs. 1 and 3.

In using the closure means shown in Figs. 7 and 8 the primary closure 31 is put in place in accordance with usual practice. Then the indicator member or outer closure 3^b is screwed into engagement with the external thread on the primary closure, the resilient pawls 33, 33 engaging the teeth on the breakable portion 5^b in the manner already described. With the parts thus assembled, access to the contents of the container can be obtained only by first forcibly unscrewing the indicator member 3^b and thus causing the breaking of the top portion 5^b thereof in the manner already described.

It is to be recognized that, while the construction shown in Figs. 7 and 8 has the advantage of simplicity and low cost, it does not have all of the operative advantages incident to the other constructions which have been described. It is necessary for the primary closure 31 to be very firmly screwed into place in order to prevent any possible unscrewing thereof by reason of force 40 transmitted thereto from the indicator member 3^b through the pawls 33, 33; but this is not a serious objection as it is the usual practice to apply considerable force in screwing such a closure into place. The lower portion of the indicator member 3^b cooperates with the bead on the bottle to prevent the insertion of a tool for the purpose of turning the primary closure 31.

In Fig. 9 there is shown a construction which differs from what is shown in Figs. 1 to 8 in that 50 the indicator member or outer closure engages directly with the container instead of being retained in place by the inner or primary closure. The construction is in this respect similar to some 55 of the constructions disclosed and claimed in our before-mentioned copending application Serial No. 723,865. This construction is included herein in order to illustrate another use for a primary closure of the type illustrated in Figs. 7 and 8.

The sheet metal primary closure shown in Fig. 9 is or may be the same as the closure 31 shown in Figs. 7 and 8 and further description thereof is unnecessary. The indicator member or outer closure 36 is formed with an internal thread 37 adapted to engage an external thread 38 formed 65 on the bottle 39. The indicator member or outer closure 36 is provided with a readily breakable indicator portion 40 similar to the portion 5 of the outer closure shown in Figs. 1 and 3, this being provided with teeth adapted to cooperate with the resilient pawls 33, 33 formed integrally with the primary closure 31. The manner of use of the closure means shown in Fig. 9 is substantially the same as already described and repetition is unnecessary.

- While the constructions shown in Figs. 1 to 3, in Figs. 4 to 6, and in Figs. 7 and 8 differ extensively as to details, they are equivalent in general principle. In each construction there is provided a 5 normally non-rotary means separate from the container and held against removal therefrom solely by the primary closure and adapted to be engaged by the thread on the indicator member to hold the said member in place.
- 10 In the constructions shown in Figs. 1 to 3 the ring 11 with its thread 12 constitutes the normally non-rotary means separate from the container 1 and held against removal therefrom solely by the primary closure 7, and the thread 12 of the said 15 ring is adapted to be engaged by the internal thread on the indicator member 3 to hold the said member in place. It is only the closure 1 which resists, or can resist, any force tending to move the ring 11 directly upward, and the ring in turn, by 20 reason of the thread 12, resists any force tending to move the indicator member 3 directly upward.
- In the constructions shown in Figs. 4 to 6 the yoke 21 with its pawls 26 constitutes the normally non-rotary means separate from the container 1 25 and held against removal therefrom solely by the primary closure 7^a, and the pawls 26 on the said yoke are adapted to be engaged by the internal thread on the indicator member 3^a to hold the said member in place. It is only the closure 7^a 30 which resists, or can resist, any force tending to move the yoke 21 directly upward, and the yoke in turn, by reason of the pawls 26, resists any force tending to move the indicator member 3^a directly upward. The said indicator member 3^a 35 prevents any access to the yoke 21 and in this way prevents the said yoke from being disengaged from the primary closure, but the said indicator member has no function in holding, or assisting in holding, the yoke against removal.
- 40 In the constructions shown in Figs. 7 and 8, the external thread formed as an integral part of the primary closure 3^b constitutes the normally non-rotary means separate from the container 30 and held against removal therefrom solely by the 45 primary closure, and the said external thread is adapted to be engaged by the internal thread on the indicator member 3^b to hold the said member in place. It is only the closure 3^b which resists, or can resist, any force tending to move the external thread thereon directly upward, and the 50 said external thread in turn resists any force tending to move the indicator member 3^b directly upward.
- What we claim is:
- 55 1. The combination of a container having an opening with an adjacent external thread, a primary closure and an internally threaded indicator member at least partly enclosing the closure and interconnected therewith through the medium of the said internal thread so that the closure prevents direct upward movement of the indicator member while permitting relative rotative movement controlled by the said thread, the said primary closure having an internal thread 60 in engagement with the container thread and serving to close the container opening and the said indicator member being free from any engagement with the container tending to prevent direct upward movement, and a normally concealed 65 means associated with the closure and the indicator member and adapted to permit the aforesaid relative rotative movement of the indicator member in the direction to screw it into its normal position but adapted to automatically engage and 70 break the indicator member upon relative rotative 75

movement thereof in the opposite unscrewing direction.

2. The combination in a container closure means, of a primary closure adapted to normally close a container opening, an externally visible 5 readily breakable internally threaded indicator member structurally separate from the closure and adapted to at least partly cover it to prevent removal thereof while the indicator member is in place and unbroken, normally non-rotary 10 means separate from the container and held against direct upward removal therefrom solely by the primary closure and adapted to be engaged by the thread on the indicator member to hold the said member in place, and a normally concealed 15 means associated with the closure and the indicator member and adapted to permit free rotative movement of the indicator member in the direction to screw it into its normal position in relation to the container but adapted to automatically engage and break the indicator member upon rotative movement thereof in the opposite unscrewing direction.

3. The combination in a container closure means, of a primary closure adapted to normally 25 close a container opening, an internally threaded outer closure structurally separate from the primary closure and adapted to entirely cover it and having an integral portion constituting an externally visible readily breakable indicator, normally non-rotary means separate from the container and held against direct upward removal therefrom solely by the primary closure and adapted to be engaged by the thread on the outer closure to hold the said outer closure in place, 35 and a normally concealed means associated with the primary and outer closures and adapted to permit free rotative movement of the outer closure in the direction to screw it into its normal position in relation to the container but adapted 40 to automatically engage and break the indicator portion of the outer closure upon rotative movement thereof in the opposite unscrewing direction.

4. In a container closure means, the combination of a primary closure adapted to normally close a container opening, an internally threaded outer closure structurally separate from the primary closure and adapted to entirely cover it and having an integral portion constituting an 50 externally visible readily breakable indicator, a normally non-rotary metallic device separate from the container and from the primary closure and held against direct upward removal from the former solely by the latter, the said device 55 being adapted to be engaged by the thread on the indicator member to hold the said member in place, and a normally concealed means associated with the closure and the indicator member and adapted to permit free rotative movement of the 60 indicator member in the direction to screw it into its normal position in relation to the container but adapted to automatically engage and break the indicator member upon rotative movement thereof in the opposite unscrewing direction.

5. In a container closure means, the combination of a primary closure adapted to normally close a container opening, an externally visible readily breakable internally threaded indicator member structurally separate from the closure 70 and adapted to at least partly cover it to prevent removal thereof while the indicator member is in place and unbroken, a metallic device separate from the container and from the primary closure and held against direct upward removal 75

from the former solely by the latter, the said device being adapted to be engaged by a portion of the container to prevent relative rotation and being adapted to be engaged by the thread on

5 the indicator member to hold the said member in place, and a normally concealed means associated with the closure and the indicator member and adapted to permit free rotative movement of the indicator member in the direction to screw it 10 into its normal position in relation to the container but adapted to automatically engage and break the indicator member upon rotative movement thereof in the opposite unscrewing direction.

15 6. A container closure means comprising in combination, a primary closure adapted to normally close a container opening, an internally threaded outer closure structurally separate from the primary closure and adapted to entirely cover 20 it and having an integral portion constituting an externally visible readily breakable indicator, a normally non-rotary externally threaded ring surrounding the primary closure and separate therefrom, the said ring being held against removal from the container solely by the primary closure and being adapted to be engaged by the thread on the indicator member to hold the said member in place, and a normally concealed means 25 associated with the closure and the indicator 30 member and adapted to permit free rotative movement of the indicator member in the direction to screw it into its normal position in relation to the container but adapted to automatically engage and break the indicator member upon 35 rotative movement thereof in the opposite unscrewing direction.

7. A container closure means comprising in combination, a primary closure adapted to normally close a container opening, an internally threaded outer closure structurally separate from the primary closure and adapted to entirely cover it and having an integral portion constituting an externally visible readily breakable indicator, an externally threaded ring surrounding the primary 40 closure and separate therefrom, the said ring being held against removal from the container solely by the primary closure and being adapted to be engaged by a portion of the container to prevent relative rotation and being engaged by the thread on the indicator member to hold the said member in place, and a normally concealed means associated with the closure and the indicator member and adapted to permit free rotative movement of the indicator member in the 45 direction to screw it into its normal position in relation to the container but adapted to automatically engage and break the indicator member upon rotative movement thereof in the opposite unscrewing direction.

50 8. The combination of a primary closure adapted to normally close a container opening, an internally threaded outer closure structurally separate from the primary closure and adapted to entirely cover it and having an integral portion 55 at the top constituting an externally visible readily breakable indicator, and a normally non-rotary metallic yoke separate from the container and engaging the primary closure to prevent upward removal therefrom, the said yoke having portions at opposite sides adapted to be 60 engaged by the thread on the outer closure to hold the said outer closure in place and having an integral portion at the top adapted to permit free rotative movement of the outer closure in the direction to screw it into its normal position in relation to the container but adapted to automatically engage and hold the said teeth and 65

in relation to the container but adapted to automatically engage and break the indicator portion of the outer closure upon rotative movement thereof in the opposite unscrewing direction.

7. The combination of a primary closure adapted to normally close a container opening, an internally threaded outer closure structurally separate from the primary closure and adapted to entirely cover it and having an integral portion at the top constituting an externally visible readily breakable indicator and having internal teeth formed thereon, and a normally non-rotary metallic yoke separate from the container and engaging the primary closure to prevent upward removal therefrom, the said yoke having portions at opposite sides adapted to be engaged by the thread on the outer closure to hold the said outer closure in place and having integral resilient pawls at the top adapted to snap over the teeth on the indicator of the outer closure during rotative movement of the said closure in the direction to screw it into its normal position in relation to the container but adapted to automatically engage and hold the said teeth and thereby break the said indicator portion upon rotative movement of the said closure in the opposite unscrewing direction.

10 8. The combination of a primary closure adapted to normally close a container opening, an internally threaded outer closure structurally separate from the primary closure and adapted to entirely cover it and having an integral portion at the top constituting an externally visible readily breakable indicator, and a metallic yoke separate from the container and engaging the primary closure to prevent upward removal therefrom and adapted to engage the container to prevent rotation relative thereto, the said yoke having portions at opposite sides adapted to be engaged by the thread on the outer closure to hold the said outer closure in place and having an integral portion at the top adapted to permit free rotative movement of the outer closure in the direction to screw it into its normal position in relation to the container but adapted to automatically engage and break the indicator portion of the outer closure upon rotative movement thereof in the opposite unscrewing direction.

15 9. The combination of a primary closure having an internal thread adapted to engage an external thread on a container and adapted to normally close the container opening, the said primary closure being provided with external ratchet teeth, an internally threaded outer closure structurally separate from the primary closure and adapted to entirely cover it and having an integral portion at the top constituting an externally visible readily breakable indicator having internal teeth formed thereon, and a metallic yoke separate from the container and engaging the primary closure to prevent upward removal therefrom and adapted to engage the container to prevent rotation relative thereto, the said yoke having portions at opposite sides adapted to be engaged by the thread on the outer closure to hold the said outer closure in place and having resilient pawls adapted to engage the ratchet teeth on the primary closure to prevent rotation thereof and the said yoke also having integral resilient pawls at the top adapted to snap over the teeth on the indicator of the outer closure during rotative movement of the said closure in the direction to screw it into its normal position in relation to the container but adapted to automatically engage and hold the said teeth and 20

thereby break the said indicator portion upon rotative movement of the said closure in the opposite unscrewing direction.

12. In a container closure means, the combination of a primary closure adapted to normally close a container opening, an outer closure structurally separate from the primary closure and adapted to entirely cover it and having an integral portion at the top constituting an externally visible readily breakable indicator, a metallic yoke separate from the container and engaging the primary closure to prevent upward removal therefrom and adapted to engage the container to prevent rotation relative thereto, the said yoke having resilient pawls at opposite sides adapted to permit the outer closure to be moved freely downward into its normal position and to prevent upward movement thereof, and means at the top of the primary closure adapted to permit free rotative movement of the outer closure in one direction but adapted to automatically engage and break the indicator portion of the outer closure upon rotative movement thereof in the opposite direction.
13. In a container closure means, the combination of a primary closure adapted to normally close a container opening, an outer closure structurally separate from the primary closure and adapted to entirely cover it and having an integral portion at the top constituting an externally visible readily breakable indicator, and a metallic yoke separate from the container and engaging the primary closure to prevent upward removal therefrom and adapted to engage the container to prevent rotation relative thereto, the said yoke having resilient pawls at opposite sides adapted to permit the outer closure to be moved freely downward into its normal position and to prevent upward movement thereof and the said yoke having an integral portion at the top adapted to permit free rotative movement of the outer closure in one direction but adapted to automatically engage and break the indicator portion of the outer closure upon rotative movement thereof in the opposite direction.
14. The combination in a container closure means, of a primary closure adapted to normally close a container opening and having an external thread formed integrally thereon, an outer closure structurally separate from the primary closure and adapted to entirely cover it and having an integral portion constituting an externally visible readily breakable indicator, the said outer closure having an internal thread adapted to engage the external thread on the primary closure, and a normally concealed means associated with the primary and outer closures and adapted to permit free rotative movement of the outer closure in the direction to screw it into its normal position in relation to the container but adapted to automatically engage and break the indicator portion of the outer closure upon rotative move-

ment thereof in the opposite unscrewing direction.

15. The combination in a container closure means, of a sheet metal primary closure adapted to normally close a container opening and having a peripheral thread exposed both internally and externally and adapted to engage an external thread on the container, an outer closure structurally separate from the primary closure and adapted to entirely cover it and having an integral portion constituting an externally visible readily breakable indicator, the said outer closure having an internal thread adapted to engage the said thread on the primary closure, and a normally concealed means associated with the primary and outer closures and adapted to permit free rotative movement of the outer closure in the direction to screw it into its normal position in relation to the container but adapted to automatically engage and break the indicator portion of the outer closure upon rotative movement thereof in the opposite unscrewing direction.

16. The combination in a container closure means, of a sheet metal primary closure adapted to normally close a container opening and having a peripheral thread exposed both internally and externally and adapted to engage an external thread on the container, the said primary closure having at the top upward projecting integral resilient pawls, and an outer closure structurally separate from the primary closure and adapted to entirely cover it and having an internal thread adapted to engage the said thread on the primary closure and also having at the top an integral portion constituting an externally visible readily breakable indicator with internal teeth formed thereon, the said teeth being adapted to pass freely over the aforesaid resilient pawls during rotative movement of the outer closure in the direction to screw it into normal position but being adapted to be engaged by the said pawls to break the indicator portion of the outer closure upon rotative movement in the opposite unscrewing direction.

17. A sheet metal primary closure adapted to normally close a container opening and having a peripheral thread exposed both internally and externally and adapted to engage an external thread on the container, the said primary closure having at the top upward projecting integral resilient pawls adapted to freely snap over internal teeth formed on a readily breakable top portion of a threaded outer closure during rotative movement of the outer closure in the direction to screw it into normal position and also adapted to engage and hold the said teeth to break the indicator portion of the outer closure upon rotative movement in the opposite unscrewing direction.
